CARL CULMAN
By John N. Brumley,
His Attorney.

UNITED STATES PATENT OFFICE.

CARL CULMAN, OF MAPLEWOOD, MISSOURI.

JEWEL-SETTING TOOL.

1,261,716.

Specification of Letters Patent. Patented Apr. 2, 1918.

Application filed April 3, 1916. Serial No. 88,662.

To all whom it may concern:

Be it known that I, CARL CULMAN, a citizen of the United States, and residing at Maplewood, county of St. Louis, State of Missouri, have invented a certain new and useful Improvement in Jewel-Setting Tools, of which the following is a specification.

This invention relates to a combination tool used by watch repairers.

- 10 One of the objects of this invention is to provide a tool which can be used for setting the jewels in a pallet, and which is so constructed that one jewel may be set without interfering with the setting of the other.
- 15 Another object is to provide a tool adapted to be used to set the jewel with respect to a roller-table of a balance, and more especially, one which will set the jewel with respect to a double roller table.
- 20 Further objects are to provide a tool of the type described which can be used for various other operations in the repairing of a watch or a clock.

Further objects will appear from the detail description taken in connection with the accompanying drawing, in which:

- Figure 1 is a perspective view of a tool embodying this invention;
- Fig. 2 is a bottom view;
- 30 Fig. 3 is a section on the line 3—3, Fig. 2;
- Fig. 4 is a top view, but with the clamping means omitted; and,
- Fig. 5 is a section on the line 5—5, Fig. 2.
- This tool is an improvement on the tool illustrated in United States Patent No. 817,955, April 17, 1906. As in the tool illustrated in the patent, it comprises a handle 1, the forward end of which is bifurcated to form a ringlike spring structure 2 and arms 3, these jaws being extended laterally to form thermally separated heating plates or wings 4, adapted to be impinged by a flame as hereinafter described. In this tool, however, the arms 3 are extended forwardly, as shown at 5, to form tapering end jaws. The jaws are connected by a screw 6 threaded into one jaw, and having a loose swivel bearing in the other jaw, the swivel bearing being formed by an annular groove 7 in the screw, and the jaw being peened in, as shown at 8, to form lugs taking into the grooves to form the swivel connection. With this construction, the jaws can be spread apart or brought together by adjustment of the screw 6.

Mounted on the handle 1 is a clamp 9 of

spring steel, the end 10 of which is slotted, as shown at 11, to receive the shank of a set screw 12, which is threaded into the handle, a concave spring washer 13, of usual construction, being interposed between the screw head and the end of the clamp, so as to frictionally clamp the same in position on the handle. A set screw 14 is threaded into the clamp intermediate of its ends, and bears 65 on the body or handle of the tool. The forward end of the clamp is bent downwardly, as shown at 15, and forwardly, as shown at 16, to form a bifurcated end corresponding with the bifurcated jaws of the tool body. 70 It will be particularly noted that under this construction the bifurcated part of the clamp straddles the space between the separated jaws 3, and presents independent portions adapted to coact respectively with 75 said jaws in clamping a watch element therein. Now inasmuch as the jaws 3 are thermally separated, in order that one of said jaws may be heated without transmitting this heat to the other jaw, it is apparent that through the medium of the clamp having separated portions adapted, 80 respectively, to the separate jaws, provision is made for clamping onto either of the jaws, an element to be heated by the heat 85 applied to that particular jaw without incurring the risk of this heat being transmitted through the clamps to the other jaw or an element which may be held thereon. This is of marked importance in the efficient 90 operation of the device, for the reason that the integrity of the thermal separation of the jaws is thus positively insured. It will be understood that the end 10 of the clamp extends flush with the tool handle for some 95 distance on each side of the pivot, whereby a bearing is formed which will tend to hold the bifurcated end of the clamp down on the jaws. The jaws are raised either by hand or by the adjustment of the screw 100 14. With this construction, furthermore, the clamp can be swung upon its pivot 12 laterally with respect to said base or can, through the slot or screw connection 11—12 moved longitudinally so as to position the 105 ends 16 of the clamp in any desired relation with respect to the jaws.

The jaws 3 are provided with plates 17 similar in construction and operation as in the patent referred to, these plates being 110 pivoted on the arms by screws 18 and having beveled ends 19 and pointed ends 20, adapted

to coöperate with graduations 21 on the arms. A pallet 22, of any suitable construction, is thus adapted to be supported on the jaws 3 with the pallet jewels 23 in engagement with the faces 19, the pallet being clamped to the jaws by means of the bifurcated end 16 of the clamp, the bearing or staff 24 of the pallet passing between the jaws 3 and the end 16 of the clamp. With this construction, permitting its longitudinal movement, the pallet can be positioned as desired.

The jaws are grooved longitudinally, as shown at 25, so that any suitable article, such as a balance staff 26, Fig. 2, or a roller table 27, Fig. 4, may be held between the jaws. Furthermore, the pointed ends of the jaws adapt this device to be used as an ordinary pair of forceps. The jaws are apertured or recessed, as shown at 28, to receive a roller table 29, in order to position the roller table with respect to a jewel or ruby pin 30 clamped between the jaws. In the double roller table, the latter is provided with an upper flange 31, to which the jewel is attached, and a lower flange 32, in which is the crescent. Now, with this construction, in which the jaws are grooved, and in which the apertures or recesses 28 extend into the grooves, the roller table can be positioned so that the lower flange 32 extends into the groove, thereby enabling the jewel or ruby pin 30 to be positioned close to the flange 32, at the same time allowing sufficient material between the recesses and the edge of the jaw to give ample strength. The jaws may further be provided with nicks or grooves 33, so that the jewels or staffs may be readily held in position. The roller table is held in place, during the application of the ruby pin, by means of the clamp, and the adjustable connection of this clamp enables the jaw to be placed directly over the roller table.

It will thus be seen that a tool is provided which is adapted to be used for a variety of purposes and operations. At the same time, it is simple in construction as well as operation, and is, therefore, cheap to manufacture. The operations of applying and adjusting the jewels to and with respect to a pallet and roller table, are well known, and a detail description of these operations is, therefore, unnecessary. Suffice it to say that the jewels are usually attached by shellac, which is softened by heating. In this case, the heating is accomplished by applying a flame to the extended plates 4, and owing to these plates being thermally separated, through the medium of the spaced jaws 3 and bifurcated structure 2, heat may be applied to either of said plates without being transmitted to the other or to the handle 1.

It is obvious that various changes may be made in the details of construction without departing from the spirit of this invention, and it is, therefore, to be understood that this invention is not to be limited to the specific construction shown and described.

Having thus described the invention, what is claimed is:

1. A jewel setting tool comprising a base constructed and arranged to provide a pair of distinct, thermally separated jaws adapted to support a watch element, a clamp operative for holding the watch element on said base, said clamp being common to both of said jaws, and means sustaining said clamp for lateral movement with respect to the said base, adapting said clamp to be shifted to positions for proper coaction with either of said jaws to clamp the watch element.

2. A jewel setting tool comprising a base constructed and arranged to provide a pair of distinct thermally separated jaws adapted to support a watch element, and a clamp mounted on said base and having a bifurcated part formed to straddle across the separated jaws and present portions disposed to coact respectively with said jaws, adapting said clamp to hold a watch element on either of said jaws thermally distinct from the other jaw.

3. A jewel setting tool comprising a base having thermally separated heating plates forming jaws adapted to clamp a jewel, one of said jaws being recessed to receive a roller table, adapted to position the same with respect to the clamped jewel, and means for clamping the roller table on said jaw.

4. A jewel setting tool comprising a bifurcated base forming jaws adapted to clamp a jewel, one of said jaws being formed to receive one flange of a roller table and position the other flange of the roller table with respect to the clamped jewel.

5. A jewel setting tool comprising a bifurcated base forming jewel clamping jaws, one of said jaws being grooved longitudinally and recessed to receive a roller table, whereby a jewel may be positioned with respect to the roller table.

6. A jewel setting tool comprising a bifurcated base forming a pair of coöoperating jaws, one of said jaws having a longitudinal groove and a recess crossing said groove.

7. A jewel setting tool comprising a bifurcated base forming a pair of coöoperating jaws, said jaws being grooved longitudinally on their opposing faces, and clamping means coöperating with said jaws.

8. A jewel setting tool comprising a bifurcated base adapted to support a pallet, means for retaining the pallet on said base, said base being extended to form end clamping jaws.

9. A jewel setting tool comprising a bifurcated base adapted to support a pallet, means for retaining the pallet on said base, said base being extended to form end clamping jaws.

base being extended laterally to form heating plates and longitudinally to form end clamping jaws.

10. A jewel setting tool comprising a base 5 constructed and arranged to provide a pair of distinct, thermally separated jaws adapted to support a pallet, means on said base for positioning the pallet jewels relatively on said jaws, and means for clamping the 10 pallet on said base, said clamping means having a bifurcated end formed to straddle across the separated jaws and present portions disposed to coact respectively with said jaws in clamping the pallet on the base.
15. 11. A jewel setting tool comprising a base having thermally separated heating plates forming jewel clamping jaws, said jaws being recessed and having their jewel engaging faces provided with grooves intersecting, respectively, said recesses, and a clamp 20 constructed and arranged for coöperating with said jaws to hold a watch element.
12. A jewel setting tool comprising a base

having thermally separated heating plates forming jewel clamping jaws, one of said 25 jaws being recessed to receive a roller table, pallet positioning plates mounted on said jaws, and a clamp adjustably connected with said base for movement to position for clamping an element in the recess or on said 30 positioning plates.

13. A jewel setting tool comprising a base having thermally separated heating plates, a spring clamp having sliding connection 35 adjacent to one end thereof on said base, adapting said clamp for endwise movement longitudinally of said base, means on said base coöperating with said clamp in one adjusted relation thereof to hold one form of watch element and in another adjusted relation thereof to hold another form of watch element, and a tensioning screw for said clamp.

In testimony whereof I affix my signature this 11th day of March, 1916.

CARL CULMAN.
